Warner 2" 1-Gallon Plastic Paint Mixer. Date First Available on Amazon.com Dec. 18, 2020. <https://www.amazon.com/Warner-1-Gallon-Plastic-Paint-447/dp/B000I1QA0U/ref> (Year: 2020).*

Primary Examiner — Ricky Pham*(74) Attorney, Agent, or Firm* — Alan G. Towner(57) **CLAIM**

The ornamental design for mixing impeller, as shown and described.

DESCRIPTION

FIG. 1 is a top perspective view of a mixing impeller showing our new design;

FIG. 2 is a bottom perspective view thereof;

FIG. 3 is a front view thereof;

FIG. 4 is a right side view thereof;

FIG. 5 is a top view thereof; and,

FIG. 6 is a bottom view thereof.

The broken lines are for environmental purposes only and form no part of the claimed design.

The mixing impeller of the embodiment of FIGS. 1-6 is rotationally symmetrical at 120° intervals around a central vertical axis thereof.

1 Claim, 3 Drawing Sheets(56)
